MODULAR CHAIR

David Weinstock, 116 W. 81st St.,
New York, N.Y. 10024

Continuation-in-part of design application Ser. No. 22,288,
Apr. 6, 1970. This application June 28, 1971, Ser. No.
157,806

Term of patent 14 years

Int. Cl. D6—01

U.S. Cl. D6—26

FIG. 1 is a front perspective view of my design for a modular chair;

FIG. 2 is a front elevational view of the chair;

FIG. 3 is a plan view of the chair;

FIG. 4 is an elevational view of the chair taken at one side thereof, the view on the other side being the same;

FIG. 5 is a rear elevational view of the chair;

FIG. 6 is a longitudinal section taken in the plane indicated by line 6—6 in FIG. 3, in order to show the back wall contours of the seating area;

FIG. 7 is a transverse section taken in the plane and indicated by line 7—7 in FIG. 3, in order to show the side wall contours of the seating area;

FIG. 8 is a front perspective view of my design for a modular chair which has the same cubical body design as the chair shown in FIGS. 1 to 5, but is provided with legs rather than a pedestal.

The dominant design motif common to the chair embodiments illustrated in FIGS. 1 and 8, is characterized by a box-like molded body having a cut-out therein,

whose configuration is such that the top face of the body has a U-shaped opening whereas the front face thereof has a trapezoidal opening and the seating area which extends between the top face and the front face is so contoured as to define sloping back and side walls which merge with a concave seating recess to define an inner chair surface which generally conforms to that portion of the body of the sitter received thereby.

This application is a Continuation-in-Part of my pending application Ser. No. D. 22,288, filed Apr. 6, 1970.

I claim:

The ornamental design for a modular chair, as shown and described.
